SCRAP METAL BALING PRESS

George W. Langford and Alford C. Barrows, Ann Arbor, Mich., assignors to Economy Baler Company, Ann Arbor, Mich., a corporation of Michigan

Application April 25, 1941, Serial No. 390,239

14 Claims. (Cl. 78—0.5)

1

The present invention relates to baling presses and more particularly to horizontal presses for baling sheet metal scrap.

Horizontal baling presses of the character described generally comprise a rectangular chamber into which scrap to be baled is thrown, a cover longitudinally slidable of the chamber into and out of covering relation with a material receiving opening in the chamber, and one or more platens in the chamber for compressing scrap metal therein when the cover is in closed position. The general arrangement is to provide two platens, one moving longitudinally of the chamber and a second one moving crosswise of the chamber after the longitudinally moving platen has travelled its complete course. The resulting bale has a width and depth as determined by the respective movements of the platens and a height determined by the distance from the bottom of the chamber to the cover. It will be understood from the foregoing description that the bales thus formed are compressed in the direction of their width and depth, but not in the direction of their height. Accordingly, the resulting bales are not as dense as they might be if they were compressed in the direction of their height.

According to the present invention, the aforementioned type of baling press is provided with a cover which as it traverses the opening of the compressing chamber into closing relation therewith, is so supported that it is inclined with its leading edge higher than its trailing edge, the leading edge being yieldingly elevated so that when the cover is in closing relation with the opening of the chamber, the leading edge of the cover may be forced downwardly into the chamber to swing the cover downwardly to compress the material therein in a direction of the height of the bale to be formed. The result of traversing the cover across the baling chamber opening while in an inclined position is that more loose scrap may be disposed in the chamber prior to baling and therefore, with the benefit of the vertical compressing a denser and heavier bale is produced. Another feature of the present invention is to provide an ejecting structure for finished bales.

An object of the present invention is to provide a scrap metal baling press or the like with a cover, the leading edge of which is elevated above the trailing edge and is subsequently movable into compressing relation with material in the compressing chamber.

Another object of the invention is to provide a scrap metal baling press of the character de-

scribed with wheeled supporting means whereby the cover for the compressing chamber may be moved from a position at one side of the compressing chamber opening across the opening into closing relation therewith, the wheeled supporting means having means for resiliently elevating the leading edge of the cover while the same is being moved across the chamber opening and for subsequently moving the leading edge downwardly into compressing relation with material in the compressing chamber.

A further object of the invention is to provide a scrap metal baling press or the like with a bale ejector selectively operable upon the return of the compressing chamber cover to its open position.

A still further object of the invention is to provide a scrap metal baling press or the like with an ejector for bales formed therein which comprises a shelf outlining a portion of the compressing chamber and on which the bale is formed.

These and other objects residing in the arrangement, combination and construction of the parts will be apparent from the following specification when taken with the accompanying drawings, in which

Fig. 1 is a section through a baling press according to the present invention taken on the line I—I of Fig. 2 showing the toggle cover depressing construction in different positions,

Fig. 2 is a plan view of a baling press according to the present invention,

Fig. 3 is a section taken on the line III—III of Fig. 1, showing details omitted from Fig. 1 for the purpose of clarity of illustration,

Fig. 4 is a section taken on the line IV—IV of Fig. 1,

Fig. 5 is a section taken on the line V—V of Fig. 3,

Fig. 6 is an enlarged view of a portion of the structure disclosed in Fig. 1 showing details,

Fig. 7 is a section corresponding to a portion of Fig. 1, disclosing an alternative form of cover depressing construction,

Fig. 8 is a section corresponding to Fig. 7 showing the parts in another position,

Fig. 9 is a partial plan view of the structure shown in Fig. 7,

Fig. 10 is a side elevation of a part of a baling press according to the present invention, having attached thereto bale ejecting mechanism, details of which are omitted from the aforesaid figures for the sake of clarity of illustration,

3

Fig. 12 is a vertical section of a portion of another form of the invention, and Fig. 13 is a section on the line XIII—XIII of Fig. 12.

Referring particularly to Figs. 1 and 2 of the drawings, the reference character 1 indicates in general a frame in which is provided a compressing chamber 2, having side walls 3, a bottom 4, and an end wall 5. The chamber 2 is provided with an open top closable by a cover 6. For the sake of simplicity of illustration, the side members 3 and the cover 6 have been shown as thick solid members. However, it will be understood that these parts of the construction may be constructed of structural members and sheets or otherwise, if desired.

The end of the chamber 2 opposite the end wall 5 is constituted by a platen 7, movable under the action of a piston rod 8 actuated by a piston 9 in a hydraulic cylinder 10. In one of the side walls 3 adjacent the end wall 5 is a second platen 11, shown in Fig. 1, and actuated by a hydraulic cylinder and piston assembly 12, disclosed in Fig. 2. It will be understood that the platen 11 moves at right angles to the direction of movement of the platen 7.

Supported by the frame 1 is a reservoir 13 for hydraulic fluid and on the top of the reservoir 13 is supported a pump 14. In front of the reservoir 13 is an operator's platform 15. Suitable remote controls, not disclosed, are supported adjacent the operator's platform 15 for enabling an operator on the platform 15 to control the movement of the various operative parts of the baling press.

The cover 6 is supported at its rear end by wheels 20, riding on the top of extensions 21 of the side walls 3. Appropriately supported above the paths of the wheels 20 are bars 19 which serve to prevent the rear end of the cover 6 from lifting during operation. At the front, the cover 6 is resiliently suspended from a carrier 22, provided with wheels 23, which ride on the top of plates 24, secured to the tops of the side walls 3 and having the inside edges thereof in vertical alignment with the inside edges of the walls 3. The plates 24 serve as loading platforms to facilitate the loading of unwieldy pieces into the compressing chamber 2 and their inner edges constitute short vertical extensions to the side walls 3. When the cover 6 is at the extreme right position, as viewed in Fig. 1, the opening of the top of the compressing chamber 2 is completely uncovered. In all positions of the cover 6, its rear portion is supported by the wheels 20 in such a manner that it is disposed between the side wall extensions 21 and guided thereby. Furthermore, as the cover 6 is traversed across the opening of the chamber 2, it is guided by the side wall extensions 21 or the side walls 3 and is maintained in an inclined position as shown particularly by the dotted position of the cover 6 in Fig. 1.

The carrier 22 for the cover 6 is in the form of a housing having suspended from the top thereof rods 25. To the lower ends of the rods 25 are connected stops 26. About the rods 25 are disposed helical springs 27, resting on the stops 26. Projecting upwardly from the top of the cover 6 are a pair of U shaped brackets 28, having openings 29 in the top thereof, through which the rods 25 project. The helical springs 27 are arranged on the parts of the rods 25 which are beneath the openings 29. The U shaped brackets 28 each have one leg 32 thereof provided with

a turned over foot 31, shown particularly in Fig. 5, which is secured directly to the top of the cover 6. The other legs 30 of the brackets 28 are secured to the upstanding leg of the angle bar 33, shown in Figs. 5 and 11 which is in turn secured to the top of the cover 6 and extends thereacross as shown in Fig. 11. The effect of the brackets 28, the rods 25, and the springs 27 is to resiliently suspend the cover 6 from the top of the carrier 22.

Secured to the top of the carrier 22 are two pairs of ears 34, and secured directly beneath the ears 34 to the angle bar 33 are two pairs of ears 35. Pivoted between each pair of ears 34 about pins 36 are toggle bars 37 and pivoted between each pair of ears 35, about pins 38, are toggle bars 39. The toggle bars 37 and 39, respectively, are pivotally connected by pins 40. The toggle bars 37 are provided at their inner ends with forks 41, between which the toggle bars 39 are pivoted. Also pivoted between the forks 41 and to the pins 40 are links 42. The links 42 are also pivoted to the ends of a bar 43, shown in Figs. 1, 3 and 6. Extending through the bar 43 is a piston rod 50, actuated by a piston 51, in a hydraulic cylinder 52.

The piston rod 50 extends through an opening 53 in one side of the carrier 22 and is guided for axial, sliding movement in a bearing sleeve 54, secured in the opposite side of the carrier 22. In order to prevent the bar 43 from oscillating about the axis of the piston rod 50, a conventional key and keyway arrangement, not shown, disposed between the rod 50 and the carrier 22 may be employed or some suitable structure may be provided such, for instance, as shown in Fig. 9 and described hereinafter.

Longitudinal movement of the piston rod 50 is transmitted to the bar 43 by a collar 55, consisting of a pair of nuts fixed to the piston rod 50. The bar 43 is resiliently held against the collar 55 by a helical spring 56, disposed about the portion of the piston rod 50 between the bar 43 and the bearing sleeve 54. Since the toggle bars 39 are connected through the ears 35 and the angle bar 33 to the cover 6, the spring 56 as the result of its collapsing action on the toggles will tend to assist the springs 27 in resiliently suspending the cover 6 from the top of the carrier 22.

The cover 6 is moved from open to closed position through the toggles comprising the toggle bars 37 and 39 by the piston rod 50. The toggles remain collapsed as shown in dotted outline in Fig. 1 and in Fig. 6, and the forward end of the cover 6 is relatively above the rear end, as shown in dotted outline in Fig. 1 for all cover positions except in final baling position. It will be understood that as the cover 6 moves either to the right or to the left, as viewed in Fig. 1, a portion of the cover 6 will be disposed either between the extensions 21 of the compressing chamber sides 3 or between the sides 3 so that the cover 6 is guided by the sides 3 or the extensions 21 for straight movement.

The frame 1 is provided at the left end, as viewed in Fig. 1, with a pair of standards 57, secured to the plates 24, and tied together with a bar 58. Connected to the standards 57 are vertical stops 59 for limiting the leftward movement of the carriage 22 under the action of the piston rod 50, as shown in Fig. 1. Also secured to the standards 57 are horizontal stops 60 reinforced on their upper sides with gusset plates 61.

In operation, after the compressing chamber

2 has been filled with material to be baled, the carrier 22 is moved to the left by the piston rod 50. The toggles within the carrier 22 will remain collapsed due not only to the action of the spring 56, but also due to the action of the springs 27 in suspending the cover 6 from the top of the carrier 22. In order to prevent swaying of the cover 6, in a direction from front to rear, during its movement into and out of closing relation with the compressing chamber 2, the carrier 22 is provided at each side thereof with a pair of vertically extending spaced bar members 62. Slidably disposed between the pairs of bar members 62, respectively, are guiding bars 63 secured to plates 64, which are in turn secured, as shown in Figs. 3 and 5, to the U shaped brackets 28. The guiding bars 63 and pairs of bars 62 also constitute a driving connection between the carrier 22 and the cover 6 to work with the toggles in transferring pushing or pulling action from the carrier 22 to the cover 6.

When the carrier 22 is moved to the left in closing direction by the piston rod 50, the carrier 22 at the end of its path of movement abuts against the vertical stops 58 and stops under the horizontal stops 60. At this position the cover 6 is in full closing relation with the compressing chamber 2. With the resistance encountered as the result of carrier 22 abutting against the stops 58, continued movement on the piston rod 50 to the left will cause the toggles comprised by the toggle bars 37 and 39 to straighten out as shown in full lines in Fig. 1. Since the carrier 22 is prevented from moving upwardly by the horizontal stops 60 under which it has moved, the effect of the toggles is to force the cover 6 downwardly into compressing relation with material in the compressing chamber 2.

The portion of the piston rod 50 between the bar 43 and the guiding sleeve 54 is provided with a sleeve member 70, shown in Fig. 6, secured to the guiding sleeve 54, and another sleeve member 71, secured to the bar 43. The lengths of the sleeves 70 and 71 are arranged so that when the adjacent ends of the sleeves abut one and another, the toggles are in their straight or dead center positions.

The lengths of the toggle bars 37 and 39 should be so arranged that when in straight or dead center position the cover 6 will no longer be inclined as it was when the toggles were collapsed, but will be parallel to the bottom 4 of the compressing chamber 2. The cover is held in this position while the platen 7 is moved to the left into alignment with the nearest edge of the platen 11, and then the platen 11 is moved laterally across the compressing chamber 2 to complete the formation of the bale. Since the baling press, according to the present invention, is designed for baling sheet metal scrap, it is not necessary to provide any arrangement for tying the compressed material together as the parts of the baled material will interlock with one and another of their own accord. However, should it be desired to employ the baling press according to the present invention, for baling some other material, it will be apparent to those skilled in the art that conventional changes may be made in the structure to permit the tying of the bale while under compression.

In Figs. 7, 8 and 9 is shown an alternative form of construction for moving the front end of the cover 6 downwardly into compressing relation with the material in the compressing chamber 2. Except for the carrier 73 and its associated struc-

ture for moving the cover 6 downwardly, the press disclosed in Figs. 7, 8 and 9 is the same as the one disclosed in Figs. 1 through 6. The cover 6 is suspended from the carrier 73 by the same rods 25, springs 27, and U shaped brackets 28, as disclosed in Fig. 3. Also, the side walls of the carrier 73 are provided with pairs of upwardly extending bars 62 in the same manner as shown in Fig. 5 and have slidably disposed between them, respectively, guiding bars 63 which instead of being secured to plates 64 as disclosed in Fig. 5 are secured to plates 74, secured to the top of the cover 6. The piston rod 50 projects through an opening 77 in the wall of the carrier 73 toward the piston 51, and inside the carrier 73 as shown in Fig. 7, is reduced in diameter to provide a shoulder 78. Abutting against the shoulder 78 is a collar 79. The reduced portion of the piston rod 50 extends through the carrier 73 and through a guiding sleeve 80, secured in the wall 81 of the carrier 73, opposite the opening 77.

The end of the piston rod 50 projected through the carrier 73 is connected to an I beam 82, which extends transversely of the press, as shown in Fig. 9. The I beam 82 is maintained against oscillating about the axis of the piston rod 50 with respect to the carrier 73 by a pair of pins 83, one disposed on each side of the piston rod 50. Each pin 83 is slidably disposed through an opening 84 in the carrier 73 and is provided with a head 85, which is secured to the I beam 82.

At each end of the I beam 82 are secured camming members 86 in the general form of plates, provided with camming surfaces 87 and hocks 88. At the left end of the baling press, as viewed in Figs. 7 and 8, are disposed on opposite sides, standards 90, each of which has pivoted thereto, about a pin 91, a swinging arm 92. Each arm 92 has a tail piece 93 to which is connected a spring 94 in turn connected to a bracket 95 extending from the standard 90. The springs 94 urge the tail pieces 93 respectively against stops 96 to resiliently urge the arms 92 to the positions illustrated by Fig. 7. The free end of each arm 92 is provided with a roller 97, pivoted about a pin 98. Each pin 98 projects laterally into the path of movement of one of the camming surfaces 87.

The portion of the piston rod 50 within the carrier 73 has disposed thereabout a helical spring 100. Under normal conditions the expansion of the helical spring, which abuts against the collar 79 and the guiding sleeve 80, tends to resiliently maintain the relation between the carrier 73 and the piston rod 50, which is shown in Fig. 7. When the piston rod 50 is moved to the left, as viewed in Fig. 7, to move the cover 6 in closing direction, the resiliency of the spring will maintain the collar 79 against the inside wall of the carrier 73 and the I beam 82 relatively close to the carrier 73. As the cover 6 reaches its extreme closed position, it abuts against the end wall 99 of the chamber 2, since the cover always has a portion thereof within the chamber 2. However, due to the yielding of the spring 100, the piston rod 50 continues to move to the left, compressing the spring 100, as illustrated in Fig. 8. This movement projects forwardly the I beam 82 and with it the camming surfaces 87 to bring the camming surfaces 87 into contact with the laterally projecting pins 93 of the arms 92. As the piston rod 50 continues to move to the left, the arms 92 are cammed downwardly, and as they are cammed downwardly, the rollers 97 are forced into con-

7

tact with bench 102, built up on and extending across the upper surface of the cover 6 to force the cover 6 downwardly into parallel relation with the bottom of the chamber 2. The forward movement of the camming surfaces 87, and thus of the I beam 82 and the piston rod 50 is limited by a collar 103 disposed loosely about the spring 100. The length of the collar 103 is designed so that when it simultaneously abuts against the collar 79 and the guiding sleeve 80, as shown in Fig. 8, the arms 92 will be in vertical or dead center position with respect to the cover 6. As the pins 98 move down the camming surfaces 87, they will move into the hooks 88 so that when in the position disclosed in Fig. 8, with the cover 6 fully depressed, the pins 98 rest within the hooks 88. The purpose of the hooks 88 is to withdraw the arms 92 from dead center position upon initial rearward movement of the piston rod 50 carrying with it the camming surfaces 87. Upon rearward movement of the piston rod 50, after the bale has been formed in the manner hereinabove described, the springs 100 will expand as the collar 79 moves rearwardly until it abuts against the rear wall of the carrier 13. The action of the collar 79 against the rear wall of the carrier 13 will result in opening the cover 6, the force being transmitted through the carrier 13, the forward bars 62 and the guiding bars 63. When the camming surfaces 87 have withdrawn from contact with the pins 98, the springs 94 will yieldingly urge the tail pieces 93 of the arms 92 against the stops 96 to hold the arms 92 in position for the next closing action of the cover 6.

A feature of the invention which may be employed with either of the forms heretofore disclosed consists of a bale ejector, disclosed in Figs. 10 and 11. For the purpose of illustration, the ejector is shown in association with the baling press disclosed in Figs. 1 through 6. The ejector consists of an L shaped member 110, having a foot portion 111, disposed in a recess 112, in the bottom floor of the compressing chamber 2. The member 110 also has a vertical leg 113, which when within the baling chamber 2 rests against the end wall 5 of the compressing chamber 2. The upper end of the leg 113 is secured rigidly to a drum 114, pivoted in the frame 1 about a shaft 115. On one end of the drum 114, which projects over one side of the press structure is secured a sheave 116. The sheave 116 has secured to its periphery one end of a short piece of flexible cable 117 by a suitable securing pin 118. The cable 117 passes part way around the sheave 116 and the other end thereof is fastened to a rod 119 by a connector 120. The rod 119 is slidably supported in guides 121, secured to the side of the press structure.

Overhanging the same side of the press structure as that on which the rod 119 is mounted is a bracket 122, which is secured to the carrier 22. The bracket 122 is provided with an enlarged opening 123 through which the rod 119 extends and has pivoted thereto about a pin 124 a latch 125, which is in the form of a plate, having a slot 126, having a width of substantially the diameter of the rod 119. The latch 125 is provided with an actuating handle 127. For operative relation with the latch 125, the rod 119 is provided with a ball 130 fixed thereto. The ball 130 is of such a size that it will pass through the opening 123 in the bracket 122, but will not pass through the slot 126 in the latch 125.

In operating the ejector according to the present invention the ejector member 110 is disposed

within the compressing chamber 2 before the material to be baled is loaded therein. It will be understood that the ejector structure is not disclosed in relation to any of Figs. 1 through 9 for the purpose of simplifying those disclosures. As shown in Figs. 10 and 11, the ejecting member 110 has a width equal to that of the finished bale 131 and a depth as measured by the length of the foot 111, which is slightly less than the depth of the finished bale 131. When the compressing chamber 2 is filled with material to be baled, the bale is formed in the manner hereinabove described. The position of the ejecting member 110 is such that the bale 131 is formed thereon. The recess 112, in which the foot portion 111 of the ejecting member 110 is disposed, is provided to prevent scrap metal being baled from forcing its way beneath the foot member 111.

When the bale 131 has been formed on the ejecting member 110, and the platens 7 and 11, shown in Fig. 1, withdrawn, the cover 6 is removed from over the compressing chamber 2 by moving the carrier 22 to the right, as viewed in Fig. 10, under the action of the piston rod 50. Previously to this stage of the operation, but following the closing of the cover 6, the handle 127 is swung downwardly, as viewed in Fig. 11, to move the latch 125 to position the slot 126 over the rod 119. As the carrier 22 moves to the right opening the cover 6, it carries the latch 125 which engages with the ball 130 to draw the rod 119 to the right. The rod 119 draws on the flexible cable 117 to rotate the drum 114 and in this manner swing the attached ejecting member 110 together with the bale 131 thereon, to the position shown in dotted outline in Fig. 10. As the foot portion 111 of the ejecting member 110 swings from the recess 112 within which it is disposed, its outer end follows the curved side 132 of the recess 112. The curved side 132 is provided to reduce the part of the recess 112 not occupied by the foot portion 111 to a minimum while at the same time providing clearance to permit the swinging out of the foot portion 111. When the ejecting member 110 reaches its uppermost position, the inclination of the leg 113 thereof is sufficient to permit the bale 131 to slide downwardly therefrom under the action of gravity. The ejecting member 110 may then be returned to its position within the compressing chamber 2, either by moving the carrier to the left to permit the weight of the ejector member 110 to lower itself into the chamber 2, at the same time drawing the rod 119 through the cable 117 to the left, or by raising the handle 127 to remove the latch 125 from behind the ball 130 to permit the ball 130 to move to the left through the opening 123 in the bracket 122 so that the ejector 110 may gravitate into the compressing chamber 102 in position for a new cycle of operation.

Another form of the invention is disclosed in Figs. 12 and 13. In this form the swinging arms 139 for forcing the cover 6 downwardly into compressing relation with the material in the compressing chamber 2, after the cover 6 has been moved laterally to closing relation with the chamber 2, are pivoted from the cover 6 carrier 140 rather than from a part of the baling press frame 141. The carrier 140 is similar to the carrier 22 disclosed in Fig. 1 and the cover 6 is suspended therefrom by structure identical with the suspending structure disclosed in Fig. 3. The suspending structure consists of a pair of rods 25 secured to the top of the carriage 140, each rod projecting through the top of the U-shaped

bracket 28, having one leg thereof supported from the top of the cover 6 and the other leg thereof supported from an angle bar 33 extending across the top of the cover 6. At the bottom of each rod 25 is disposed the stop 26, and between each stop 26 and the top of the associated bracket 25 is a spring 27, the springs 27 carrying the weight of the cover 6.

The carriage 140 is reciprocated by a piston rod 142 corresponding to the piston rod 50 disclosed in Fig. 1. The driving connection between the carriage 140 and the cover 6 is the same as the driving connection between the carriage 22 and the cover 6 as disclosed in Figs. 3 and 5, and more particularly consists of a pair of spaced bar members 62 secured to each side of the carriage 140 between each pair of which is vertically disposed a guiding member 63 secured to a plate 64. Each plate 64 is secured to the outside of the lower portion of one of the U-shaped brackets 28.

The carriage 140 is driven from the rod 142 through a spring 143 disposed about the left end of the rod 142 as viewed in Fig. 12. A collar 144 secured to the rod 142 bears against one end of the spring 143. The other end of the spring 143 bears against an annular plate 145 disposed on the forward end of the carriage 140. The outer end of the piston rod 142 is guided in openings 146 in the carriage 140. As the piston rod 142 is moved to the left, the cover 6 is resiliently moved in a closing direction, the force exerted by the piston rod 142 being transmitted to the spring 143 to the carriage 140, and from the carriage 140 through the bar members 62 to the guiding members 63. Return movement of the cover 6 is accomplished by reversing the direction of movement of the rod 142 to bring a collar 147 on the rod 142 in engagement with the rear side of the carriage 140.

Each arm 139 is pivoted between ears 148, the ears 148 being provided with vertical slots 149. Pins 150 fixed to the arms 139 extend through the slots 149. Each arm extends through the top of the carriage through a slot 151 between the ears 148. The arms 139 are rocked about their pins 150 by rollers 152 supported by a bracket 153 secured to the rod 142, the rollers 152 bearing against a plate 154 bridging the arms 139. The tension of the spring 143 is sufficiently great to permit the closing of the cover 6 until it abuts against the forward end wall 99 on the chamber 2. When the cover 6 meets the resistance of the end wall 99, the spring 143 is compressed permitting the bracket 153 to move forwardly under the action of the rod 142 to move the rollers 152 into engagement with the bar 154, to pivot the arms 139 about their pivots 150.

As the rod 142 moves forwardly the rollers 152 swing the arms 139 about their pivots 150 until the arms 139 are in a vertical position. The arms 139 are stopped in a vertical position by stops 155 secured to the front wall of the carriage 140 in the path of movement of the respective arms 139. As the arms 139 are swung about their pivots 150, rollers 156 on the upper ends thereof move rearwardly along horizontal stops 157 secured to parts of the frame 1. As the stops 157 are fixed, the lower ends of the arms 139 swing downwardly as well as forwardly, the slots 149 permitting downward movement of the pivots 150. The lower ends of the arms 139 are provided with rollers 158 which bear against the top of the cover 6, as the arms 139 swing downwardly and forwardly to cam the cover 6 downwardly, compressing the material in the chamber 2 to be 75

baled. It will be understood that as soon as the cover 6 has been swung downwardly into the chamber 2 by the arms 139, the compressing platens 7 and 11 disclosed in Fig. 1 are actuated to compress the material in the chamber 2.

When the material in the chamber 2 has been compressed into a bale, the rod 142 is moved rearwardly. The initial movement of the rod 142 releases the compression in the spring 143 and at the same time through a bracket 159 extending forwardly from the bracket 153 engages with the forward sides of the arms 139 to swing the arms 139 rearwardly to permit the cover 6 to be elevated by the springs 27. Continued rearward movement on the rod 142 brings the collar 147 thereon into engagement with the rear wall of the carriage 140 to move the carriage 140 and with it the cover 6 rearwardly to open the chamber 2.

While we have described one form of the invention where arms are pivoted to the cover 6 carriage, it will be understood that other forms employing arms pivoted to the carriage may be used. Also, while the foregoing specification has described a press for baling as such, it will be understood that the invention may be employed for other forms of compressing and molding operations, and accordingly, we do not wish to be limited except by the scope of the following claims.

We claim:

1. A press of the character described comprising a compressing chamber, said chamber having a material receiving opening at one side thereof, a rigid cover for said opening, means to support said cover at one side of said opening and in general alignment therewith, means to traverse said cover across said opening into closed relation with the same, said first means supporting said cover while being traversed across said opening in inclined relation to said chamber with its forward part disposed relatively outwardly of said chamber from its rear part, means to move said forward part of said cover relatively inwardly of said chamber into alignment, relatively to said chamber, with said rear part of said cover when said cover is in closed relation to said chamber, platen means in said chamber, and means to move said platen means to compress material in said chamber.

2. A press of the character described comprising a frame, a compressing chamber in said frame, said chamber having a material receiving opening at one side thereof, a rigid cover for said opening, said chamber having a side opposite said opening and in a general plane, means for supporting said cover from said frame for movement from a position at one side of said opening and in general alignment therewith across said opening to close the same, said supporting means having means for supporting said forward part of said cover, while being moved across said opening, further outwardly from the plane of the side of said chamber opposite said opening, than said rear part thereof, means to move said cover across said opening into closed relation therewith, means to move said cover, when in closed relation to said chamber, into substantially parallel relation with said plane, platen means in said chamber, and means to move said platen means to compress material in said chamber.

3. A press of the character described comprising a compressing chamber, said chamber having a material receiving opening at one side thereof, a rigid cover for said opening, means

to support said cover at one side of said opening, means to traverse said cover across said opening into closed relation with the same, said first means supporting said cover, while being traversed across said opening, in inclined relation to said chamber, with its forward part disposed relatively outwardly of said chamber from its rear part, means to move said cover relatively inwardly of said chamber when said cover is in closed relation with said chamber, platen means in said chamber, and means to move said platen means to compress material in said chamber.

4. A press of the character described comprising a compressing chamber, said chamber having a material receiving opening at one side thereof, a rigid cover for said opening, means to support said cover at one side of said opening, means to traverse said cover across said opening into closed relation with the same, said first means supporting said cover, while being traversed across said opening, in inclined relation to said chamber, with its forward part disposed relatively outwardly of said chamber from its rear part, means over said cover when it is in closed relation with said chamber for bearing on the top of said cover to move it relatively inwardly of said chamber when in closed relation therewith, platen means in said chamber, and means to move said platen means to compress material in said chamber.

5. A press of the character described comprising a frame, a compressing chamber in said frame, said chamber having a material receiving opening at one side thereof, a rigid cover for said opening, means to support said cover at one side of said opening, means to traverse said cover across said opening into closed relation with the same, said first means supporting said cover, while being traversed across said opening, in inclined relation to said chamber, with its forward part disposed relatively outwardly of said chamber from its rear part, said frame having thrust resisting means adjacent the end of said chamber toward which said cover moves on closing, means over said cover when in closed position to exert a force on the top of said cover to move the same relatively inwardly of said chamber, means providing a thrust resisting connection between said thrust resisting means and said cover moving means to back up said cover moving means when moving said cover relatively inwardly of said chamber, platen means in said chamber, and means to move said platen means to compress material in said chamber.

6. A press of the character described comprising a frame, a compressing chamber in said frame, said chamber having a material receiving opening at one side thereof, a rigid cover for said opening, means to support said cover at one side of said opening, means to traverse said cover across said opening into closed relation with the same, said first means supporting said cover, while being traversed across said opening, in inclined relation to said chamber, with its forward part disposed relatively outwardly of said chamber from its rear part, said frame having thrust resisting means adjacent the end of said chamber toward which said cover moves on closing, swinging arm means having a thrust resisting connection with said thrust resisting means when said cover is in closed relation with said chamber, means to actuate said swinging arm means to move said cover inwardly of said chamber when said cover is in closed relation with said chamber, the cover moving force exerted by said swinging arm means being resisted by said thrust

resisting means, platen means in said chamber, and means to move said platen means to compress material in said chamber.

7. A press of the character described comprising a compressing chamber, said chamber having a material receiving opening at one side thereof, a rigid cover for said opening, means to support said cover at one side of said opening, means to traverse said cover across said opening into closed relation with the same, said first means supporting said cover, while being traversed across said opening, in inclined relation to said chamber, with its forward part disposed relatively outwardly of said chamber from its rear part, means to stop the closing movement of said cover when it reaches closed relation with said chamber, means operative upon continued operation of said cover traversing means after said cover has stopped moving to swing said forward part of said cover inwardly of said chamber into alignment relatively to said chamber with said rear part of said cover, platen means in said chamber, and means to move said platen means to compress material in said chamber.

8. A press of the character described comprising a compressing chamber, said chamber having a material receiving opening at one side thereof, a rigid cover for said opening, means to support said cover at one side of said opening, means to traverse said cover across said opening into closed relation with the same, said first means supporting said cover, while being traversed across said opening, in inclined relation to said chamber, with its forward part disposed relatively outwardly of said chamber from its rear part, swinging arm means over said cover when it is in closed relation with said chamber for bearing on the top of said cover to move it relatively inwardly of said chamber when in closed relation therewith, means for actuating said swinging arm means when said cover is in closed relation with said chamber, platen means in said chamber, and means to move said platen means to compress material in said chamber.

9. A press of the character described comprising a compressing chamber, said chamber having a material receiving opening at one side thereof, a rigid cover for said opening, means to support said cover at one side of said opening, means to traverse said cover across said opening into closed relation with the same, said first means supporting said cover, while being traversed across said opening, in inclined relation to said chamber, with its forward part disposed relatively outwardly of said chamber from its rear part, means to stop the closing movement of said cover when it reaches closed relation with said chamber, swinging arm means operative upon continued operation of said cover traversing means, after said cover has stopped moving, to swing said forward part of said cover inwardly of said chamber into alignment relatively to said chamber with said rear part of said cover, means for providing an operative connection between said swinging arm means and said cover traversing means, platen means in said chamber, and means to move said platen means to compress material in said chamber.

10. A press of the character described comprising a frame, a compressing chamber in said frame, said chamber having a material receiving opening at one side thereof, a rigid cover for said opening, means to support said cover at one side of said opening, means to traverse said cover across said opening into closed relation with the

same, said first means supporting said cover, while being traversed across said opening, in inclined relation to said chamber, with its forward part disposed relatively outwardly of said chamber from its rear part, swinging arm means pivoted to said frame, means resiliently projecting said swinging arm means over said cover when in closed relation with said chamber, means associated with said cover traversing means for engaging said swinging arm means as said cover reaches its closed position to swing said swinging arm means into engagement with said cover, to cam said forward part of said cover relatively inwardly of said chamber into alignment relatively to said chamber with said rear part of said cover, plate means in said chamber, and means to move said platen means to compress material in said chamber.

11. A press of the character described comprising a frame, a compressing chamber in said frame, said chamber having a material receiving opening at one side thereof, a rigid cover for said opening, means for supporting said cover for movement from one side of said opening across said opening into closed relation with the same, said means including a carriage adjacent the forward part of said cover, toggle mechanism within said carriage, one end of said toggle mechanism being connected to said carriage, and the other end of said toggle mechanism being connected to said cover, actuating mechanism for said toggle mechanism, resilient means for maintaining said toggle mechanism in collapsed position and for maintaining said forward part of said cover disposed relatively outwardly of said chamber from its rear part, whereby said cover is maintained in inclined relation to said chamber, means to move said toggle mechanism actuating means to move said cover into closed relation with said chamber, abutment means on said frame for stopping the movement of said cover when it reaches closed relation with said chamber, abutment means on said frame operative to prevent outward movement of said carriage with respect to said chamber when said cover is in closed relation with said chamber, whereby upon continued movement of said toggle actuating means said toggle mechanism is straightened to urge said forward part of said cover inwardly of said chamber, platen means in said chamber, and means to move said platen means to compress material in said chamber.

12. A press of the character described comprising a frame, a material receiving chamber in said frame, said chamber having a material receiving opening at one side thereof, a rigid cover for said opening, a carriage adjacent the forward end of said cover, means for resiliently suspending said forward end of said cover from said carriage, means resiliently connected to said carriage for moving the same over said opening to traverse said cover across said opening into closed relation with the same, an overload connection between said carriage and said cover for producing relative movement in cover opening and closing directions between said carriage and said cover, said overload connection upon predetermined resistance to movement producing relative movement between said carriage and said cover toward and away from said opening, said resiliently suspending means for said cover supporting said forward part of said cover relatively outwardly of said chamber from the rear part of said cover whereby during traversing movement of said cover the same is in inclined relation to 75

said chamber, means associated with said carriage moving means to move said forward end of said cover relatively inwardly of said chamber when said cover is in closed relation with said chamber, platen means in said chamber and means to move said platen means to compress material in said chamber.

13. A press of the character described comprising a frame, a material receiving chamber in said frame, said chamber having a material receiving opening at one side thereof, a rigid cover for said opening, a carriage adjacent the forward end of said cover, means for resiliently suspending said forward end of said cover from said carriage, means to traverse said cover across said opening into closed relation with the same, pre-loading means between said carriage and said cover for producing relative movement in cover opening and closing directions between said carriage and said cover, said preloading means upon predetermined resistance to movement producing movement of said cover with respect to said carriage toward and away from said opening, said resiliently suspending means for said cover supporting said forward part of said cover relatively outwardly of said chamber from the rear part of said cover whereby during traversing movement of said cover the same is in inclined relation to said chamber, said preloaded means including toggle mechanism within said carriage, one end of said toggle mechanism being connected to said carriage and the other end of said toggle mechanism being connected to said cover, a connection between said toggle mechanism and said cover traversing means, resilient means for maintaining said toggle in collapsed position during traversing movement of said cover, means to stop the movement of said cover when it reaches closed position, whereby upon continued motion of said cover traversing means, said toggle mechanism is actuated to straighten the same to urge said forward part of said cover inwardly of said chamber, means to limit the actuation of said toggle, platen means in said chamber, and means to move said platen means to compress material in said chamber.

14. A press comprising a frame, a material receiving chamber in said frame, said chamber having a material receiving opening at one side thereof, a sliding rigid cover for said opening, anti-friction means supporting the rear part of said cover, track means supporting and guiding said anti-friction means for substantially horizontal sliding movement of said cover for opening or closing said material opening, a carriage slideable on said track means, means on said carriage suspending the forward part of said cover from said carriage, said last named means being constructed and arranged to support the forward part of said cover elevated above the material receiving opening of said chamber but allowing vertical movement of said forward part for engagement of said cover with the material in said chamber yet restraining movement of said cover relative to said carriage in a direction of said trackway, means for stopping the forward movement of said carriage and thereby said cover, when said cover is over said receiving opening, means on said carriage and engaging said cover for thereafter forcing said cover in its vertical movement against the material in said chamber, and means for sliding said cover and for actuating said last named means.
